W. E. McDONELL.
OPHTHALMIC MOUNTING.
FILED MAY 10, 1922.

William E. M. DONELL INVENTOR.

BY *David & Sonnenschein*
his ATTORNEYS.

UNITED STATES PATENT OFFICE.

WILLIAM E. McDONELL, OF ROCHESTER, NEW YORK, ASSIGNOR TO SHUR-ON OPTICAL COMPANY, INC., OF ROCHESTER, NEW YORK, A CORPORATION OF NEW YORK.

OPHTHALMIC MOUNTING.

Application filed May 10, 1922. Serial No. 559,837.

To all whom it may concern:

Be it known that I, WILLIAM E. McDONELL, a citizen of the United States, and resident of Rochester, in the county of Monroe and State of New York, have invented certain new and useful Improvements in Ophthalmic Mountings, of which the following is a specification.

The present invention relates to ophthalmic mountings and more particularly to the type in which the frame of the mounting embodies two rings formed of non-metallic material and connected by a bridge of the same material all in an integral structure. An object of this invention is to provide a construction which will make it unnecessary for dealers to hold in stock a large number of differently sized mountings in order to be able to meet different facial characteristics. A further object of the invention is to provide for connecting nose rests to a non-metallic mounting in such a manner that the adjustment of the rests will not disconnect the latter from the mounting. A further object of the invention is to provide a simple and inexpensive connection between the adjustable arm of a nose rest and a non-metallic mounting.

To these and other ends, the invention consists of certain parts and combinations of parts, all of which will be hereinafter described; the novel features being pointed out in the appended claims.

In the drawings:

Fig. 1 is a rear view of a mounting constructed in accordance with this invention, the temples being shown in section;

Fig. 2 is an enlarged fragmentary section on the line 2-2, Fig. 3;

Fig. 3 is an enlarged fragmentary section showing the connection between the adjustable supporting arm and the non-metallic frame;

Fig. 4 is a view similar to Fig. 3 of another embodiment of the invention; and

Fig. 5 is a rear view of a mounting constructed in accordance with the embodiment illustrated in Fig. 4.

Referring more particularly to the drawings, 1 indicates the lens rings made of non-metallic material such as zylonite or the like and connected by a bridging portion 2 also made of the same material and integral with the rings. The temples 3 pivotally

connect at 4 to extensions 5 provided on opposite sides of the frame.

A pair of pads or nose rests 6 are arranged to engage on opposite sides of the nose of the wearer and with the temples 3 serve to support the mounting on the user. 60 These pads or nose rests have sleeves 7 on their rear faces mounted to turn on adjustable supporting arms connected with the frame.

In the embodiment of the invention 65 shown in Figs. 1 to 3, these supporting arms are formed of pliable or ductile metal wire bent to provide a portion 8 on which the sleeve 7 turns, a portion 9 at one side of the sleeve to cooperate with the rear face 70 of the rest 6, in order to limit the swinging movement of the latter, and a bend 10 connecting with the portion 8 and also with a portion 11 extending forwardly above the sleeve. At the forward end of the portion 11 a laterally turned or U shaped portion 12 is provided. This laterally turned or U shaped portion is embedded in the non-metallic material adjacent the junction between the bridging portion and one of 80 the rings, this result being secured by heating the anchoring or U shaped portion 12 and then forcing said portion into the non-metallic material which flows about the U shaped portion, so that the latter finally 85 assumes the position illustrated in Fig. 3. After the non-metallic material is cooled, the connection is such that the pliable supporting arm may be adjusted to position the nose rest 6 so as to adapt it to the nose 90 of the wearer and this without destroying the connection between the supporting arm and the non-metallic material, the laterally turned portion preventing the supporting arm from turning in the non-metallic 95 material.

In the embodiment of the invention shown in Figs. 5 and 4 the parts of the frame are the same. The pads 6^a is formed in a known manner with a tubular portion 100 7^a between its ends. This pad connects with the non-metallic frame through the pliable or adjusting arm which has a portion turning in the tubular portion and from said turning portion an arm 13 105 extends downwardly connected by a bend 14 with an upwardly extending portion 15 which by a bend 16 connects with a U

shaped anchoring portion 12^a which is embedded in the non-metallic material in the same manner as the anchoring portion illustrated in the embodiment of Figs. 1 to 3.

5 From the foregoing it will be seen that there has been provided an ophthalmic mounting in which a non-metallic frame is formed from two continuous rings connected by a bridging portion and having 10 nose rests provided with supporting arms anchored in the non-metallic material adjacent the connection of the bridging portion with the rings. The connection between the supporting arms and the frame is 15 such that the supporting arms may be bent to adjust the nose rests without disconnecting the supporting arms from the non-metallic frame. This invention makes it possible for dealers in non-metallic mountings 20 of this type to reduce the variety of sizes carried in stock, as one mounting may be adjusted to fit a large number of different types of faces.

What I claim as my invention and desire 25 to secure by Letters Patent is:

1. In an ophthalmic mounting, the combination, with a frame formed of non-metallic material and embodying a pair of rings, and a bridge connecting them, of 30 nose rests each having an adjustable supporting arm provided with a rigid portion embedded in the non-metallic material adjacent the connection of the bridging portion with one of the rings and formed to 35 prevent the turning of said embedded por-

tion in the non-metallic material during the adjustment of the supporting arm.

2. In an ophthalmic mounting, the combination with a frame formed of non-metallic material and embodying a pair of 40 rings and a bridge portion connecting them, of nose rests each having an adjustable supporting arm having a laterally extending portion embedded in the non-metallic material adjacent the connection of the bridging portion with the ring.

3. In an ophthalmic mounting, the combination with a frame formed of non-metallic material and embodying a pair of 50 rings and a bridge connecting them, of nose rests each having an adjustable supporting arm provided with a U shaped end anchored in the non-metallic material adjacent the connection of the bridge portion with the ring.

4. In an ophthalmic mounting, the combination with a frame, of nose rests, each having a bearing sleeve on the rear face thereof, and pliable supporting arms for said rests, each having a portion turning in 60 a bearing sleeve, a portion extending from the forward portion of said bearing portion to co-operate with the rear face of the nose rests to limit the movement of the latter, a portion extending upwardly from the rear 65 portion of the bearing portion, and a portion extending forwardly from said upwardly extending portion and connected with the frame.

WILLIAM E. McDONELL.
